CLAIM

The ornamental design for a container for liquids, substantially as shown and described.

DESCRIPTION

FIG. 1 is a front elevational view of a container for liquids showing my new design;

FIG. 2 is a plan view thereof;

FIG. 3 is a rear elevational view thereof;

FIG. 4 is a bottom view thereof; and

FIG. 5 is a left end elevational view thereof, the right end elevation being a mirror image thereof.

FIG. 5

FIG. 3

FIG. 2

FIG. 4

FIG. 1
